SAFETY RAZOR

Benjamin F. Nicoll, Sr., New Orleans, La.

Application June 29, 1935, Serial No. 29,141

7 Claims. (Cl. 30—35)

This invention relates to safety razors and particularly to those razors which are adapted to use hollow ground razor blades having the same cross-sectional form and the same weight as the 5 blade of a barber's razor.

The general object of the present invention is to provide a holder adapted to clamp a razor blade of the character stated for use as a safety razor through which the blade may be readily 10 removed and replaced, in which the blade is clamped firmly in its shaving position within the holder but in which the blade may be released and readily pushed out of the holder for replacement or honing.

15 A further object is to provide a structure in which the blade holding head is capable of being turned to a honing position and the razor blade shifted out of the head but supported for honing or sharpening.

20 A further object in this connection is to provide means whereby the user of the safety razor can sharpen his razor blade in a simple, practical and fool-proof manner and which will enable him to keep a sharp edge on the blade at all times.

25 A further object is to provide a holder for relatively heavy razor blades, this holder being of such construction that the weight of the razor is considerably heavier than that of any other razor on the market and in which this dead weight of 30 the razor approximates the exertion put forth by a barber in shaving to thus secure a close and proper shave.

Other objects will appear in the course of the following description.

35 My invention is illustrated in the accompanying drawings wherein:

Figure 1 is a vertical section through the preferred form of razor blade holder, the blade being shown in cross-section, the section being taken on 40 the line 1—1 of Figure 2;

Figure 2 is a sectional view on the line 2—2 of Figure 1;

Figure 3 is an elevation showing the blade holding head of the holder shifted outward from the 45 handle to permit the blade holder to be turned to a stropping position;

Figure 4 is a longitudinal sectional view of the holder with the head turned into alignment with the handle;

50 Figure 5 is an elevation of the same structure shown in Figure 4 but partly in section, showing the blade projected from the holder;

Figure 6 is a plan view of the structure shown in Figure 5, showing the blade projected and in 55 position for honing or sharpening;

Figure 7 is a section on the line 7—7 of Figure 3;

Figure 8 is a longitudinal section through a modified and simpler form of holder, the razor blade being in section; 5

Figure 9 is a fragmentary elevation showing the manner in which the blade is drawn out of the head;

Figure 10 is an end elevation of a composite 10 blade;

Figure 11 is a perspective view of an implement whereby the thin razor blade shown in Figure 10 may be forced out of the back in which the blade is mounted;

Figure 12 is an end elevation of the blade such 15 as the blade shown in Figure 6, in position for honing, stropping or sharpening.

The simplest form of my invention is illustrated in Figure 8, and hence I will describe this 20 form first.

Referring to these drawings, 10 designates an outer barrel of metal and 11 a cap fitting upon the upper end of the barrel. The cap may have screw threaded engagement with the barrel or have a friction fit thereon. This cap 11 is formed 25 with a countersunk recess 12 on its underface and with a blade receiving portion 13 formed to provide two jaws 14 and 15 between which the margin of the blade is received, the recess 13 receiving the back of the blade. The other jaw 15 is 30 formed with outwardly projecting fingers 16, as shown in Figure 6, which render the razor a safety razor. The two jaws, as shown in Figure 35 8, at the entrance to the back receiving recess 13 are arched outward and forward and engage the blade adjacent its extremity. This cap is formed with a screw threaded aperture 17 and the blade at its back is formed with a recess 18.

Extending through the barrel 10 and spaced 40 from this barrel is a sleeve 19, the upper end of which is received in the countersink 12. The upper end of the sleeve 19 is formed with lugs 20 in the manner shown in Figure 7 for the razor blade holder illustrated in Figures 1 to 6, which 45 are accommodated within the countersink 12, whereby to prevent any rotation of the head 11 upon the barrel 10. Extending through the sleeve 19 is a locking rod 21. The lower end of this rod is provided with a plug 22 fitting within the lower extremity of the sleeve 10 and with a knurled 50 head 23 whereby the locking rod 21 may be rotated. The upper end of this locking rod is provided with screw threads 24. The upper end of the sleeve 19 is formed with a circular recess 25 and engaging the lower ends of the screw threads 55

24 are a pair of nuts 26 which are circular and fit within this recess. When the parts are in the position shown in Figure 8, these nuts, which have free play in the circular recess 25 will be 5 raised or spaced from the bottom of this recess so that upon rotation of the head 23, the screw threaded end of the locking rod 21 may be freely retracted from its engagement with the razor blade. When so retracted, the sleeve 19 and the 10 rod 21 may be withdrawn from the barrel 10, and then this sleeve 19 with its rod 21 may be inserted between the jaws 14 and 15 in alignment with the back of the blade A, as shown in Figure 9, and the blade A may be drawn out of the holder. 15 Instead of using the sleeve 19 for the purpose of pushing the blade out of the holder, as shown in Figure 9, an implement such as shown in Figure 11 may be used for this purpose, which has a handle B and a portion B', which has the same 20 cross section as the cross section of the blade A. It will be seen that the head of this blade holder is relatively heavy, that the blade itself is heavy and concave ground and thus it has the same weight and momentum when used as the 25 regular barber's razor has. The parts may be readily taken apart for cleaning and the blade removed at any time for stropping or honing.

In Figures 1 to 7, I have illustrated the preferred form of my invention which is, however, slightly 30 more complicated than the structure shown in Figure 8, because it provides means whereby the blade may be shifted to a honing position without detaching the head from the handle or the blade itself from the locking rod. In these 35 figures, 28 designates an outer barrel and 29 an annular plug disposed within the upper end of the barrel. The head 30 fits over the upper end of the barrel, as previously described, and is provided with a countersink 31. This head is constructed, as previously described, of two jaws 32 40 and 33, the back of the head being formed with a recess 34 constituting a continuation of the inner faces of the jaws and designed to receive the back of the blade A. This blade may be constructed either as shown in Figure 12 where the 45 end of the blade is formed with a central bore "a" and with radial recesses "a'" or may be constructed as shown in Figure 10, where the blade proper and designated C is held between the jaws of a 50 solid head D, this head having at its end the central bore "a" and the radial grooves or recesses "a'". This back D constructed as shown in Figure 10, enables a thin safety razor blade to be used in my holder. Preferably, however, a hollow-ground 55 blade, such as shown in Figure 12, will be used. One or both faces of the blade A is provided with an indentation adapted to receive the end of a locking rod as will now be described. Disposed within the barrel 28 is a sleeve 35 equivalent to 60 the sleeve 19 previously referred to, this sleeve extending through the plug 29 and into the countersink 31 in the head 30. This sleeve at its upper end, as shown in Figure 7, is provided with the diametrically disposed radial lugs 36 65 which engage in recesses formed in the bottom of the countersink 31, these lugs thus holding the head 30 from rotation relative to the sleeve 35. Extending through this sleeve 35 and through the plug 37 carried within the barrel at the lower end 70 of the sleeve 35 is a locking rod 38 of the same character as the locking rod 21 which at its upper end is screw threaded for engagement with nuts 39 disposed within the countersink 31. This screw threaded end of the locking rod extends 75 through an aperture in the head 30, as shown in

Figure 1, and into engagement with a recess in the back of the blade A so that when this locking rod is in position shown in Figure 1, it clamps the blade A in place within the head. The lower end of the locking rod 38 extends through the plug 5 37 and is connected to a knurled operating head 40 which is adapted to have sliding movement within the sleeve 28. The sleeve 28 is provided with a longitudinally extending slot 41 and with a knurled slide 42, which is shown as embracing 10 the barrel 28. A screw 43 extends through this slide and into the plug 37. Thus, it will be obvious that when this slide is shifted longitudinally along the slot 41, the plug 37, the locking rod 38 and the sleeve will be projected, as shown in 15 Figures 4, 5 and 6.

As shown in Figure 5, the slot 41 is provided with an upwardly inclined offset 44 with which the pin or screw 43 is adapted to engage when the parts are in the position shown in Figure 1, 20 and which acts to hold the parts in this position until the knurled collar or slide 42 is rotated to carry the pin 43 out of its engagement with the slot 44. Then the slide may be shifted along the barrel 28 in the manner shown in Figures 5 25 and 6.

As shown in Figures 2 and 3, the head 30 is mounted upon a hinge element 45 which is hinged, as at 46, to a sliding shank 47 which extends parallel to the side wall of the barrel and 30 bears against this side wall and extends through a slot formed in the plug 29, as shown most clearly in Figure 2. When the locking rod 38 is in locking engagement with the blade A, as shown in Figure 1, any swinging movement of the head 35 35 upon the hinge joint 46 is prevented, but when it is desired to sharpen the razor, the locking rod is retracted from its engagement with the razor blade, the head 30 is held, and the barrel 28 drawn away from the head, as shown in Figure 3, 40 to an extent permitted by the sliding bar 47 which at its end has a limiting stop 47a, which limits the movement of the barrel with relation to this sliding bar. The parts will then be in the position shown in Figure 3, and under these circumstances, the head may be swung upon the pivot 46 in a counter-clockwise direction in Figure 2 to carry the notched end of the blade A 45 downward into alignment with the locking rod, as shown in Figure 4. The locking rod is then rotated by means of the knurled handle 40 to cause the projection of the screw threaded end of the locking rod into the central screw threaded opening "a" of the blade (either the blade shown in Figure 10 or that shown in Figure 12) and carry the 50 lugs 36 on the extremity of the sleeve 35 into engagement with the recesses "a'" of the blade. The blade is then locked solidly in alignment with the sleeve 35 and with the locking rod 38. This is the position shown in Figure 4. If now the slide 42 be 55 shifted longitudinally, as shown in Figure 5, along the barrel, the sleeve 35 will be projected out of the barrel carrying with it the blade A which will be projected out of the head 30 in the manner shown in Figure 6. In this position, the 60 blade may be honed. It will be noted that the blade is hollow ground, as shown in Figure 12, and that when applied upon the hone H, the back of the blade will touch the surface of the hone and the extreme cutting margin of the 65 blade will touch the hone. The diameter of the back and the hollow grinding of the blade are so proportioned that the margin of the blade is given the proper angle to properly sharpen the blade. After the blade has been sharpened or 70 75

honed, the parts may be returned to their initial position by retracting the slide, carrying the blade into the head 30, then disengaging the locking rod from the end of the blade, then swinging the blade upon its hinge to the position shown in Figure 3, shifting the head and barrel into engagement with each other, as shown in Figure 1, and then turning the locking rod 38 to bring it into engagement with the back of the blade, as also shown in Figures 1 and 2. The blade may be removed from the blade holding jaws of the head by retracting the locking rod to free the blade and then pushing the blade out by any suitable implement, such as the implement shown in Figure 11. It will be seen that in the preferred form of my structure, the blade need not be detached from its holder in order to strop it, and that when the blade is in a position for stropping, it has been projected from the jaws of the holding head so that it is entirely free for proper contact with the strop, hone or sharpening element. It will likewise be seen, as before stated, that the blade itself is relatively heavy and the head which holds the blade is relatively heavy and this heaviness plays a very important part in the shaving operation. The weight in this razor is considerably heavier than of any other razor on the market, and this weight is of extreme importance. A barber exerts muscular energy in using what is termed the master barber's stroke, and this is part of his technique. The dead weight in the razor blade and clamping head which I have described is the equivalent of this muscular exertion put forth by the barber and in use, the blade which I have designed, slides over the face without apparent effort, the operator simply guiding the razor. This is equally true of either the upward stroke or the downward stroke. Apparently it is the momentum of the blade, due to its weight which is the equivalent of the muscular energy put forth by the barber.

In connection with the showing of the relation of the parts in Figure 3, the sleeve 35 is shown advanced slightly so that the lugs 36 are in position to engage in the groove a'. In releasing the handle from the head so that the handle can be shifted to the position shown in Figure 3, when the screw 38 is disengaged from the head and the razor held in the position illustrated in Figure 3, the screw will move longitudinally of the sleeve until its threaded end is in the relation to the lugs 36 shown in Figure 3, at which time the lock nuts will be in the bottom of the recesses in which they are disposed. The entire sleeve may then be moved longitudinally of the handle by permitting the screw 43 carried by the slide 42 to slip out of the recess 44 into the lower end of the long recess 41. This will bring the upper ends of the lugs and the end of the screw 38 into the plane of the upper end of the handle 28. At the same time that these actions are taking place, the entire handle assembly slides downwardly on the member 47. This action, as will be readily seen, effects the removal of the lugs and the threaded end of the screw 38 from their exposed positions at the upper end of the handle 28 so that undue extension of the handle on the part 47 is avoided and the handle may be conveniently swung around to its alined position with the end of the razor A in which it is shown in Figure 4.

While the drawings and description set forth the preferred design and arrangement of parts for the present invention, it is to be understood

that slight changes and modifications may be made therein so long as such changes or modifications mark no material departure from the salient features of the invention as expressed in the appended claims.

What is claimed is:—

1. A safety razor including a barrel constituting a handle, a blade clamping head detachably mounted on one end of the barrel and formed to provide a seat for the back of the blade and two jaws engaging opposite faces of the blade adjacent its edge, the ends of the head being open, a blade insertable in said head having a recess in its back confronting the barrel, the edge of the blade projecting out between said jaws, and a locking rod extending through the barrel having a knurled head at one end bearing against the adjacent extremity of the barrel, the other end of the locking rod being screw threaded for engagement through the head, the extremity of the locking rod engaging in said recess in the back of the blade.

2. A safety razor blade holder including a barrel constituting a handle, a blade clamping head having a socket receiving one end of the barrel, the head being formed to provide a seat for the back of the razor blade and two jaws engaging opposite faces of the blade, a sleeve disposed within the barrel, the socket on the head being countersunk for the reception of the sleeve and the bottom of said countersink being formed with recesses, the sleeve at its upper end having lugs engaging in said recesses and a locking rod extending through the sleeve, one end of the locking rod having a knurled head bearing against the outer end of the barrel, the other end of the locking rod being screw threaded for engagement through the head, the extremity of the locking rod impinging against the blade disposed within said head.

3. A safety razor blade holder including a head open at its ends, the head being formed to provide a seat for the back of the razor blade and two jaws engaging opposite faces of the blade, a barrel constituting a handle and inserted in the head, a sleeve disposed within the barrel and at one end having an axial recess and at this end having interlocking engagement with the head, the head having a screw threaded aperture extending from the socket for the handle into said recess for holding the back of the blade, a locking rod extending through the sleeve and at one end having a knurled head engaging against the sleeve and against the adjacent end of the barrel, the other end of said locking rod being screw threaded and engaging through the screw threaded aperture in the first named head and adapted to impinge against the blade, and nuts disposed within the axial recess in the sleeve with which said screw threads engage.

4. A safety razor blade holder including a barrel constituting a handle, a blade clamping head detachably engaged with the handle and formed to provide a seat for the back of a blade and two jaws engaging opposite faces of the blade, an element having sliding engagement with the barrel and to which the head is hinged whereby when the element is shifted outward, the head may be turned to carry one open end into alignment with the barrel, means disposed within the barrel for clamping the blade within the head and holding the head on the barrel when the head is in shaving position or forcing the blade out of the head when the head is in alignment with the barrel, said means having detachable lock-

ing engagement with the blade when the blade is in alinement with the barrel.

5. A safety razor holder including a barrel constituting a handle, a blade holding head detachably engaged with the handle, the head being open at its opposite ends and formed to provide a seat for the back of the blade and two jaws engaging on opposite faces of the blade adjacent the end thereof, an element having sliding engagement with the barrel and to which the head is hinged whereby when the element is shifted outward from the barrel the head may be turned into alinement with the barrel, a sleeve disposed within the barrel and projectable through one end of the barrel into and through said head when the head is turned into alinement with the barrel, said sleeve having means at its extremity for engaging a razor blade and holding it from rotation, said means acting when the head is in shaving position on the barrel to detachably engage the blade and hold the blade from shifting.

6. A safety razor including a barrel constituting a handle, a blade clamping head detachably engaged with one end of the barrel and normally disposed at right angles to the barrel, the head being open at its ends and being formed to provide a seat for the back of the razor blade and two jaws adapted to engage on opposite sides of the blade, a blade insertable in said head and having a relatively thick back engageable within the seat, one end of the back of the blade having a screw threaded aperture and radial recesses, an element slidably engaged with the barrel and having hinged engagement with the head to permit the head to be shifted outward from the barrel and then turned into alinement with the barrel, a sleeve disposed within the barrel and longitudinally slidable therethrough, a locking rod carried by said sleeve and extending centrally

therethrough normally projecting beyond the sleeve and having its projecting end screw threaded for engagement with the head, the extremity of the locking rod normally bearing against the back of the blade when the head is in shaving position, the locking rod being retractable through the sleeve sufficiently to disengage it from the head and blade, and means on the exterior of the barrel whereby the sleeve and the locking rod may be shifted longitudinally through the head when the latter is turned into alinement with the barrel to thus project the blade outward from the head, the extremity of the locking rod engaging with the screw threaded aperture in the blade and the extremity of the sleeve having lugs engaging in the recesses on the ends of the blade to thus prevent the blade from turning with relation to the sleeve and permit the blade to be stropped.

7. A safety razor including a barrel constituting a handle, a blade clamping head open at its ends and formed to provide a seat for the back of the blade and two jaws engaging opposite faces of the blade, an element having sliding engagement with the barrel and to which the head is hinged whereby when the element is shifted outward, the head may be turned into alinement with the barrel, means disposed within the barrel and rotatable to lock the head on the barrel with the head in shaving position, said means when the head is turned into alinement with the barrel being projectable through the head to force a blade out of said head, and a blade adapted to be disposed within the head, said means being formed to have screw threaded engagement with one end of the blade and being formed to interlock with the blade to hold the blade from rotation around the axis of said means.
